UNITED STATES PATENT OFFICE.

VINCENT G. APPLE, OF DAYTON, OHIO, ASSIGNOR TO APPLE ELECTRIC COMPANY, OF DAYTON, OHIO, A CORPORATION OF OHIO.

GEARING.

1,169,595.

Specification of Letters Patent.

Patent Jan. 25, 1916.

Original application filed October 2, 1911, Serial No. 652,381. Divided and this application filed February 27, 1913. Serial No. 750,949.

To all whom it may concern:

Be it known that I, VINCENT G. APPLE, a citizen of the United States, residing at Dayton, in the county of Montgomery and State of Ohio, have invented certain new and useful Improvements in Gearing, of which the following is a specification.

My invention relates to improvements in gearing.

10 One of the objects of my invention is to provide a speed-reducing gearing, capable of transmitting power from a rapidly rotating part to a part to be rotated at a relatively slow speed with relatively small friction-loss.

Another object of my invention is to provide a device, of the character referred to, which contains few parts; which will occupy relatively small space; and which is 15 practically noiseless in operation.

Other and further objects of my invention will become readily apparent to persons skilled in the art from a consideration of the specification when taken in conjunction with the drawings, wherein—

Figure 1 is a cross sectional view of my improved gearing taken on a plane at right angles to the axis of the main shaft, this being indicated in Fig. 2 as line 1—1. Fig. 2 30 is a cross section taken on line 2—2 of Fig. 1; and Fig. 3 is a cross section taken on line 3—3 of Fig. 2.

In all the views the same reference characters are employed to indicate similar 35 parts.

My present invention is a division from application Serial No. 652,381, filed October 2, 1911, regulator for dynamo electric machines, which application was allowed November 9, 1912.

As in the former application I have shown my reducing gear, in this application, applied to a dynamo electric machine wherein 5 is the casing or frame of the machine and 6 is a projecting armature shaft. A supplementary, gear-containing casing is provided, which is composed of the parts 7 and 8 adapted to encompass the shaft 6, and is secured to the dynamo casing 5 by means 45 of bolts 9—9, or otherwise. The shaft 6 is reduced, as at 10, and as at 11. The parts 6 and 11 are concentric but the part 10 is eccentric, as shown in Figs. 1 and 3. The casing 7 is circular in form except for the

offset 12, wherein is contained a vertical 55 shaft 13, upon which is fixed a worm wheel 14, as by a key 15. This shaft is shown broken off and is designed to be extended to any mechanism which is desired to be rotated at a relatively slow speed by the operation of the dynamo electric machine or motor. The shaft has bearings in the wall of the casing, as at 16, and a step bearing, as at 17. The screws 9—9, which are employed to secure the two parts of the casing together, may also be used for securing the casing to the casing of the dynamo electric machine, or if desired the part 7, of the gear casing may be an integral part of the dynamo electric machine and the screws 9 may 70 be employed solely for securing the part 8 in place with the part 7 of the casing.

A worm wheel, or annulus 18 is shown made in two parts, 19 and 20, the former annulus being preferably made of brass and 75 having a somewhat smaller bore to provide a shoulder between it and the preferably steel annulus 20. The latter is provided with internal gear teeth, as at 21. The two parts are secured together by rivets 22 and 80 both parts have upon their exterior periphery a continuous worm 23 that has driving engagement with the worm wheel 14. The composite wheel 18 lies snugly in a bore in the parts 7 and 8 and is adapted to be rotated therein by mechanism now to be described.

The wheel 18 travels in a concentric path around the main portions of the shaft 6 and in its rotary motion it revolves a vertical, 90 or tangentially disposed, shaft 13 by its worm and worm wheel engagement therewith. Lying inside of the steel internal gear wheel 18, and resting on the shoulder provided by the brass wheel part, by reason 95 of its larger internal diameter than the internal diameter of the part 19, is an exteriorly geared wheel 24, counterbored as at 25, and concentrically perforated as at 26 to receive the eccentric 10 on the shaft 6. 100

Inside of the counterbore, and close to the interior surface of the wheel 24, lies a spider or universal guide 27 having two relatively long arms 28 and 29 that lie in the notches 30 and 31 respectively provided 105 in the flange of the wheel 24. Two relatively short arms 32 and 33 lie in notches provided between guide lugs 34 and 35 which project

from the inner surface of the cover plate 8. Any suitable means, in lieu of the guide 27, may be employed for this purpose, which will permit proper vertical and horizontal 5 movement of the wheel 24 without permitting its rotation. In the exemplification shown such motion is imparted to the wheel 24 through the instrumentality of the eccentric 10 in conjunction with the universal 10 guide 27 in a manner clearly understood from the drawing.

The relative number of gear teeth in the internally geared member 18 and the externally geared member 24 governs the speed 15 of the former with relation to the speed of the shaft 6. In the exemplification shown the outer gear member 18 has one more gear tooth than the inner member 24 and therefore, after one revolution of the shaft, all 20 of the spaces, except one, between the teeth of the outer wheel will have been filled by the teeth of the inner wheel in successive order and the outer gear, which can be rotated freely, has been driven one tooth, or 25 one $1-n^{\text{th}}$ part of the revolution at every revolution of the shaft, or in other words, the reduction in speed between the shaft and the outer worm gear equals $1 \div N$. The speed of rotation between the worm wheel 30 on the shaft 13 and the worm that is cut on the peripheral surface of the outer gear $18 = 1 \div N^2$. This brings the total reduction in speed to

$$35 \quad \frac{1}{N} \text{ multiplied by } \frac{1}{N^2}.$$

In the present exemplification the speed

of the dynamo, used as a motor, is say 2000 R. P. M. while the rotated vertical shaft is turned 1 R. P. M. which is a reduction of 40 2000 to 1. Of course this relation may be varied by changing the geared relation of the wobbling gear with that of the rotatable gear and furthermore by changing the pitch of the worm wheel and the worm of the 45 vertical or tangential shaft 13.

It is evident that many variations may be made from the exemplification which I have chosen for a clear disclosure of my invention without departing from the spirit of 50 my invention and within the scope of the appended claim.

What I claim is:

A reduction gearing comprising a rotatable shaft provided with an eccentric part; 55 an internally geared annulus positioned for concentric rotation around the true axis of said shaft; an externally geared member overlying said eccentric part having some of its teeth intermeshing with the teeth of the overlying member, said members having different numbers of teeth; means to permit free lateral and vertical movement of the inner geared member and to prevent rotation thereof; a worm gear on the outer surface of said internally geared annulus and a shaft carrying a pinion driven by said worm. 60

In testimony whereof I hereunto set my hand in the presence of two witnesses.

VINCENT G. APPLE.

In the presence of—

N. E. SNYDER,
M. N. O'CONNOR.
